OTIS T. CRAFTS, OF MANCHESTER, NEW HAMPSHIRE

HEEL BASE AND PROCESS OF MAKING THE SAME

Application filed November 25, 1930. Serial No. 498,041.

My invention aims to provide an improved heel or heel base for boots and shoes, also an improved art or process of manufacturing a heel or base. The term "heel base" is ordinarily employed when reference is made to a low heel of two-eighths to three-eighths of an inch in height; when in excess of such height it is more commonly termed a "heel". In the present instance, for simplicity of statement, I shall refer to the subject matter of my invention as relating to heel bases, it being understood that the same process may be employed to produce articles of greater height that would be more properly called "heels".

Prior to my invention many attempts have been made to reduce the cost of making heel bases by building them up of one or more pieced layers, that is to say, layers comprising assembled pieces cut from remnants of leather as distinguished from whole layers, which latter require such large pieces from which to cut them as to render them very expensive.

Prior to my invention, however, so far as I am aware, it has been considered impracticable to employ pieced layers except in connection with whole layers, or partial layers extended transversely of the heel at one or both sides of the pieced layer, to bind the pieces of the latter together or in position against displacement during the further process of applying the heel or while the heel is in use. My invention comprehends the manufacture of a heel base of longitudinally assembled layer pieces without the necessary assembly at either side thereof of either whole layers or transversely arranged layer sections or pieces.

My invention also comprehends other features which may be used to advantage with the pieced layers above referred to or otherwise, as will more fully hereinafter appear.

In the accompanying drawing, I have illustrated one embodiment of my invention and one method for carrying it out.

In the illustrative embodiment and process shown in the drawing:—

Fig. 1 is a plan view of the bottom or sole

face of a heel base illustrating my invention;

Fig. 2 is a right-hand or rear-edge view of the base shown in Fig. 1;

Fig. 3 is a detail showing the rear end of a layer comprised of longitudinally assembled members made in accordance with my invention;

Fig. 4 is a vertical, longitudinal section of the base shown in Fig. 1, the section being taken on the dotted line 4—4;

Fig. 5 is a vertical, transverse section of the base shown in Fig. 1, the section being taken on the dotted line 5—5, looking to the right;

Fig. 6 is a side or edge elevation of a base comprising two layers made in accordance with my invention;

Fig. 7 is a back elevation or edge view of the base shown in Fig. 6;

Fig. 8 is a plan of the bottom of the rear end of a fabricated shoe with parts broken away; and

Fig. 9 is a section on the line 9—9 of Fig. 8.

Referring to the drawing, the base shown in Figs. 1 to 5 inclusive is built up of four layers, while that in Figs. 6 and 7 is built of but two layers. Since the additional height of base in Figs. 1 to 5 inclusive is obtained by superposing two of the bases shown in Figs. 6 and 7, it will be convenient, as well as more simple, to disclose my invention by referring first to Figs. 1, 3, 6 and 7.

Referring to these figures, I have provided, first, a layer *a* comprising a plurality of longitudinally assembled layer sections or pieces 8, 8, shown as two in number and of substantially identical size and shape, as best shown in Figs. 1 and 3. Each of these layer pieces comprises substantially one-half the full area of the completed layer, and both pieces may be cut out by use of one and the same die, they being assembled with their straight edges facing each other and preferably in abutting contact along the longitudinal, median line of the layer. The term "abutting contact" is employed to mean that the lift pieces are assembled one longitudinal face opposed to the other but not necessarily in actual physical contact therewith. While ordinarily the best

results will be had by actual physical abutment of one edge face against the other, it is to be understood that successful results may be had if they face each other with more or less of a space between, the degree of separation permissible being determined by all the circumstances under which they are used. In any event, at the back end of the heel it is more desirable that there be actual physical contact to avoid the necessity for filling in any gap at the exposed back of the heel.

In the vicinity of the back end of the heel, each of the lift pieces 8 is provided with a laterally extended ear portion 9, scarfed at one face to permit the two ears to overlap one upon the other along a diagonal line 10, Fig. 2, when the two pieces 8 are assembled as described. A suitable adhesive is preferably used to cement the scarfed faces of the overlapping ears to each other when they are assembled, this adhesive being applied to one or both the contacting faces before the assembly, as may be found to produce the best results.

Where a greater height of base is required than can conveniently be produced by the described assembly of two layer pieces α , such additional height may be had by employing two or more superposed layers of the same construction or, preferably, there will be overlaid upon the two-piece layer α described an additional layer β comprising two side pieces or sections 11, Fig. 1, and a transverse back section 12.

The side sections 11 may also be cut out from a single die over a run of sizes.

One of the ends of the side sections 11 is preferably cut off square to make accurate fit with the straight inner edge of the transverse back section 12, as shown in Fig. 1. This connection may be a square abutting contact or one of the ends of the side pieces may be scarfed off, as indicated at 13, Fig. 6, to underlie the similarly scarfed straight edge of the back piece 12, the two scarfed faces being preferably attached together or united as by a suitable adhesive.

It will be observed that the side pieces 11 have both edges made slightly convex to approximate the curve of the outside of the heel base in that vicinity, so that in assembling the heel, the operative may assemble the pieces with either face up and with either edge outward.

Having assembled the base, Figs. 6 and 7, as described, it is passed through a Young, Monarch or other suitable gouging machine, and one face, namely, that made up of the pieces 11 and 12, and it may be the middle portion of the layer α , is gouged to produce the desired concavity or cupping to fit the convex heel portion of the sole.

Where the desired height of the full heel base is greater than may conveniently be obtained by the two layers, Figs. 6 and 7, and it is desired to apply thereto an additional

pair or pairs of layers similarly assembled, each pair of layers made as described will preferably be gouged as described before being assembled or superposed, as indicated in Figs. 4 and 5.

In any event, after assembly of the pairs of pieced layers, Figs. 6 and 7, or Figs. 4 and 5, the assembly will be compressed in a usual heel compressor to compact the mass and give final shape to the concavity.

Where pieced layers are employed at that side of an assembly which is to be concaved, there is a practical limit to the depth of concavity that can be obtained by gouging, due to the fact that if the gouging is very deep, it is likely to cut away so much of the layer pieces as not to leave enough to be caught and held by the attaching nails when the heel is applied to the shoe, with the result that sometimes such side pieces might spring loose and obtrude at the sides of the heel. If the desired depth of concavity does not exceed the thickness of the layer pieces, there will always remain enough of width of such pieces to assure them firm attachment when the heel is applied. It is when the depth of desired concavity exceeds the thickness of the side pieces—and this is usually the case, that there is likelihood of cutting away so much of the side pieces in the gouging process as to leave insufficient width of the pieces for secure attachment when the heel is applied.

By assembling successive pairs of gouged layers, as shown in Figs. 4 and 5, this difficulty is avoided because each pair before assembly will have been gouged to a depth not to exceed the thickness of the pieced layers thereof, and when two pairs of layers so gouged are assembled or superposed as shown and are compressed, the upper pair or pairs is or are depressed into the concavity gouged in the layer beneath, so that in the finally compressed base the concavity formed is aggregate of the combined gouges of the assembled layers.

By this construction and method, an ultimate concavity may be had as deep as desired and exceeding the thickness of any one or more of the pieced layers; in fact, the gouging might be carried somewhat into the two-piece layers beneath the three-piece layers if desired, without danger of cutting away the side pieces to such an extent as to make them incapable of secure attachment by the heel nails commonly employed in attaching the heels.

The two pieces of the layer α are adequately secured together at their rear ends by the overlapping and united ears 9 and are further united by the overlapping transverse layer piece 12, which latter is usually cemented over and upon the underlying portions of the layer pieces 8, so that in the handling of the layers preparatory to attaching the base to the shoe, there is no

danger of separation of the parts in the vicinity of the back of the base.

At the breast end of the base, however, there are no overlapping edge portions to the pieces 8, nor is there any overlying piece corresponding to the member 12, consequently there may be danger in handling, that the median line of abutment contact between the members 8 may be spread. This is especially the case at the time of attachment of the heel base to the shoe or of the top,—whether of rubber or leather, to the base, where the driving of one or more attaching nails into the line of contact may spread the pieces 8.

To guard against this, after the layer has been gouged and before compression, it is presented to a staple tacker, such as is found in practically every shoe shop, and one or more metallic fastenings 14, see Figs. 1 and 5, preferably in the form of staples, are driven through and clinched, to bridge the line of abutting contact of the pieces of the layer *a*, as best shown in Fig. 5.

In the process of compression, these metallic fastenings are further impressed into and upon the pieces of leather so that they do not project appreciably above the surrounding surfaces through which they are driven, and they prevent any subsequent spreading of the layer sections 8 by the nails employed in attaching the base and tops.

Other means may be employed for securing the pieces 8, 8, in abutting relationship or contact than the metallic fastenings shown; for example, they may be stitched together.

Figs. 8 and 9 show one manner of attaching a rubber heel top to a heel seat by use of the heel base shown in Fig. 5. In this example, the heel base 15 is conveniently attached to the sole 16 by use of nails 17, while the rubber heel top 18 is afterwards applied, and attached by nails 19. In commercial practice the nailing operations preferably are carried out by use of a suitable heel nailing machine.

It will be observed that the nails 17 and 19 extend through the gouged layers well back from their feather edges and, further, that these nails act to hold the longitudinally split breast portion of the heel base in assembled relation.

A heel base made in accordance with my invention may be composed entirely of pieces—no single whole layers are required, and in the building up of the heel base, whatever the height is to be, and whatever depth of concavity is required, no waste thickness is involved because those layers *a* which make up the body of the base to but not including any part of the concavity, may be of such thickness, singly or in the aggregate, that nothing will be gouged therefrom in the formation of the concavity,—the entire concavity will be gouged from the marginal or side pieces 11 and back pieces 12 constituting

a single layer *b* or one or more multiples thereof. In other words, in building up a base, there must be a certain thickness of material extending across the entire width of the heel, to avoid leaving a concavity in the middle of the heel, and this thickness is made up of a plurality of layers *a*, and in the formation of the concavity the only layers that are gouged or cut away are the less expensive smaller pieces of the layer or layers *b*.

A superior heel base would be obtained by superposing a plurality of layers *a* one upon another, the pieces of each secured at the back by the overlapped and united ears 9 and secured forward thereof by the attaching nails that would be employed to attach the heel base to the shoe and the top to the base. I believe such a construction to be new. It would be economical in that it would be wholly built up of pieced layers and also because a single die only would be used for both the pieces 8. Such a base when built up to the ultimate over-all height required would be gouged as heretofore described. In addition to the above, the layer which is to lie next the sole might be made up of the three-piece construction of the layer *b* or of the well-known half-horeshoe sections gouged as before, to form the entire concavity by cutting.

In any event, the heel bases made hereunder will be built up to the entire over-all height of the desired completed base and wholly regardless of the thickness of the individual layers and however the layers of varying thickness may be assembled, so long as the required over-all and ultimate height is obtained, whereupon the entire concavity will be cut or gouged at a single operation on a Young, Monarch or equivalent gouging machine, as first disclosed and covered in my earlier Patent No. 1,528,912, issued March 1, 1925. Should it be deemed inexpedient to cut the full concavity in one face of the base, a part could be cut in one face and the balance in the opposite face, and compression relied upon to straighten out the oppositely gauged base to give it one plain face, which would cause the other to exhibit the entire concavity.

My invention is not limited to the process and product above disclosed but may be varied within the spirit and scope of the claims.

I claim:

1. That improvement in the art of making heels which comprises forming a heel base blank of desired over-all height and of one or more layers, by assembling for each layer a plurality of longitudinally abutted layer pieces provided at one of their ends with overlapping uniting ears; cupping a face of said base blank by gouging the assembled blank thereat; attaching the base so made by usual nails to a shoe sole and thereafter at-

taching to the top face of said base a top of the desired material, the fastening means attaching the base to the sole and the top to the base serving to retain the breast ends of said longitudinally abutted layer pieces against displacement.

2. That improvement in the art of making heels which comprises forming a heel base blank of desired over-all height and of one or more layers, by assembling for each layer a plurality of longitudinally abutted layer pieces provided at one of their ends with overlapping ears united by an adhesive; cupping a face of said base blank by gouging the assembled blank thereat; attaching the base so made by usual nails to a shoe sole and thereafter attaching to the top face of said base a top of the desired material, the fastening means attaching the base to the sole and the top to the base serving to retain the breast ends of said longitudinally abutted layer pieces against displacement.

3. That improvement in the art of making heels which comprises forming a heel base blank of desired over-all height and of one or more layers, by assembling for each layer a plurality of longitudinally abutted layer pieces provided at one of their ends with overlapping united ears; cupping a face of said base blank by gouging the assembled blank thereat; compressing the gouged base; attaching by usual nails the base so made to a shoe sole and thereafter attaching to the top face of said base a top of the desired material, the fastening means attaching the base to the sole and the top to the base serving to retain the breast ends of said longitudinally abutted layer pieces against displacement.

4. That improvement in the art of making heels which comprises forming a heel base blank of desired over-all height and of one or more layers, by assembling for each layer a plurality of longitudinally abutted layer pieces provided at one of their ends with overlapping united ears; cupping the face of said base blank by gouging the assembled blank thereat; securing the layer pieces together toward the breast end of the base by fastening means spanning the abutting assembly line; attaching the base so made by usual nails to a shoe sole and thereafter attaching to the top face of said base a top of the desired material, the fastening means attaching the base to the sole and the top to the base serving to retain the breast ends of said longitudinally abutted layer pieces against displacement.

5. That improvement in the art of making heels which comprises forming a heel base blank of desired over-all height and of one or more layers, by assembling for each layer a plurality of longitudinally abutted layer pieces provided at one of their ends with overlapping united ears; cupping a face

of said base blank by gouging the assembled blank thereat; securing the layer pieces together toward the breast ends of the base by fastening means spanning the abutting assembly line, compressing the base thus formed; attaching by usual nails the base so made to a shoe sole and thereafter attaching to the top face of said base a top of the desired material, the fastening means attaching the base to the sole and the top to the base serving to retain the breast ends of said longitudinally abutted layer pieces against displacement.

6. As an article of manufacture, a heel base comprising in combination a plurality of longitudinally abutted layer pieces provided at one of their ends with overlapping uniting ears and additionally secured against separation by a metallic fastening bridging the abutted joint.

7. As an article of manufacture, a heel base comprising in combination a plurality of longitudinally abutted layer pieces provided at one of their ends with adhesively united ears and additionally secured against separation by a metallic fastening bridging the abutted joint.

8. As an article of manufacture, a heel base comprising in combination a plurality of longitudinally abutted layer pieces provided at one of their ends with adhesively united ears and additionally secured against separation by a fastening bridging the abutted joint.

9. As an article of manufacture, a heel base comprising in combination a plurality of longitudinally abutted layer pieces united toward their breast ends by a fastening bridging the abutted joint, and a transverse layer piece overlying said longitudinally abutted pieces at one face thereof and across said abutment joint.

10. As an article of manufacture, a heel base comprising in combination a plurality of longitudinally abutted layer pieces united toward their breast ends by a fastening bridging the abutted joint, a transverse layer piece overlying said longitudinally abutted pieces at one face thereof and across said abutment joint, and a fastening additional to said transverse layer also bridging said abutment joint.

11. As an article of manufacture, a heel base comprising in combination a plurality of longitudinally abutted layer pieces provided at a face and at their rear ends with a transversely extended layer piece secured thereto and toward their opposite or breast ends with additional fastening means bridging said abutment joint, and said transverse layer pieces overlying said abutted layer piece at the same face as said transverse face and completing therewith a second layer.

12. As an article of manufacture, a heel base comprising in combination a plurality of longitudinally abutted layer pieces pro-

vided at one face and at one of their ends with a transverse layer piece, said pieces at the same face as said transverse layer piece, forming in conjunction therewith a second 5 layer, and a fastening uniting said abutting pieces and bridging the joint between the same.

13. As an article of manufacture, a heel base comprising in combination a plurality 10 of longitudinally abutted layer pieces provided at one of their faces with side and back layer pieces, the latter bridging said abutted joint and provided also with additional fastening means bridging said abut- 15 ment at a point toward the breast of said base, said base being cupped at its face formed by said side and rear pieces.

14. As an article of manufacture, a heel base comprising in combination a plurality 20 of longitudinally abutted layer pieces provided at one of their ends with overlapping, scarf'd and united ears, and additionally secured against separation by a fastening bridg- 25 ing said abutted joint.

15. As an article of manufacture, a heel base comprising in combination a plurality of longitudinally abutted layer pieces provided at one of their ends with overlapping united scarf'd ears and additionally secured 30 against separation by a fastening bridging the abutted joint, and additional side and back layer pieces secured to said longitudinally abutted layer pieces at one of the faces of the latter, said side and back layer pieces 35 having overlapped engagement with each other.

16. As an article of manufacture, a heel base comprising in combination a plurality of longitudinally abutted layer pieces pro- 40 vided at one of their ends with overlapping united scarf'd ears and additionally secured against separation by a fastening bridging the abutted joint, and additional side and back layer pieces secured to said longitudi- 45 nally abutted layer pieces at one of the faces of the latter, said side and back layer pieces having overlapped scarf'd engagement with each other.

17. As an article of manufacture, a heel base blank comprising in combination a plurality 50 of longitudinally abutted layer pieces having secured thereto at one of their faces additional side and back layer pieces, the latter bridging said abutted joint.

55 In testimony whereof, I have signed my name to this specification.

OTIS T. CRAFTS.
